UNITED STATES PATENT OFFICE.

WILLIAM FRITZ, OF PHILADELPHIA, PENNSYLVANIA.

LETTERING AND DECORATING DEVICE.

1,269,174.

Specification of Letters Patent. Patented June 11, 1918.

Application filed June 1, 1917. Serial No. 172,277.

To all whom it may concern:

Be it known that I, WILLIAM FRITZ, a citizen of the United States, residing in the city and county of Philadelphia, State of Pennsylvania, have invented a new and useful Lettering and Decorating Device, of which the following is a specification.

My present invention relates to blanks previously coated with chocolate and still in a plastic condition, and consists in novel means for discharging one or more streams of liquid chocolate upon a single blank to form letters or designs.

It further consists of a novel construction, 15 of an open work table and means for intermittently agitating and shaking the same.

It further consists of a novel construction of channels above said table and means for closing and opening the same, whereby 20 smaller or larger blanks may be kept in a straight line for receiving the decoration.

It further consists of novel means for pushing the blanks in transverse rows across the open work table.

25 It further consists of a novel construction of a feeding table, whereby the blanks are fed in longitudinal and transverse rows to said open work table.

The invention will be fully understood 30 from the following description and claims when the same are read in connection with the drawings, accompanying and forming part of this specification, in which:

Figure 1 is a side elevation, partly in vertical section, of a machine embodying my present invention.

Fig. 2 is a plan, partly in section, of the same.

Fig. 3 is an enlarged detail longitudinal section showing the organized mechanism constituting the present invention.

Fig. 4 is a top plan view of the same.

Fig. 5 is an enlarged detail view showing the means for reciprocating the lettering and decorating means.

Fig. 6 is an enlarged detail section illustrative of the lettering means.

Similar numerals of reference designate corresponding parts in all of the views of 50 the drawings.

The receiving mechanism of the machine comprises a framework 1 and bearings 2 in which are mounted the shafts 3 of transversely grooved rollers 4 which bear the endless metal ribbons 5. These ribbons are

guided and supported by a table 6, having longitudinal strips 7, and are provided with top and bottom transverse ribs 8 the lower of which engage the grooves of the transversely grooved rollers 4.

9 designates a tank mounted on legs 10, and having a water inlet 11 at the bottom and an overflow 12 at its top. A container 13 having a semicylindrical bottom and vertical walls is arranged in the tank 9 and receives a shaft 14 and paddles 16 to agitate the liquid coating in the container 13 which is kept at the proper temperature by the water in tank 9.

A lifting pump chamber 17 below and in communication with the container 13 contains an eccentrically mounted roller 18 in a diametrical slot 20 of which is a slidable piston blade 19.

From the outlet of the pump chamber 17 extends an upright pipe 21. A transverse pipe 22 at the upper end of pipe 21 has a narrow slot on its lower side for spraying liquid chocolate on top of the blanks. A lower transverse pipe 23, in communication with the pipe 21, has a narrow slot in its upper side and sprays the bottom of the blanks on the open work table. The said table has two transverse bars 24, 24 secured to the vertical sides 25. In slots of the transverse bars 24, 24, at the ends of the open work table, are secured pointed longitudinal vertical plates 26. Springs or elastic bands 27 are fastened between the bars 24, 24 and to the pointed ends of the plates 26. 28 designates a bracket riveted to the vertical sides 25 having an opening into which is loosely fitted an upright pin 29 bearing the transverse roller 30 directly beneath the elastic bands or springs 27. By the action of 95 the roller 30 and pin 29, in combination with a lever 32 and a ratchet 31 which engages said lever, the elastic bands or springs 27 will be caused to vibrate and shake the excess of coating from the blanks on the open 100 work table.

34, 34' designate longitudinal twin metal strips the lower edges of which are arranged in close proximity to the elastic bands or springs 27. The ends of said strips 105 34, 34' are bent upwardly, Fig. 3. At one end of the open-work table the said upwardly bent ends of the strips 34, 34' are fastened in slots provided in a bridge 35. At the opposite end of the open-work table 110

the upwardly bent ends of some of the strips are fastened in slots provided in a transverse bar 36 and the upwardly bent ends of the alternate strips are fastened in slots provided in a second and adjacent transverse bar 36'. Said bars 36 are mounted to move endwise in a standard 37, and journaled in an opposite standard 37' are correspondingly threaded screws 37^b which extend into and engage the bars 36 and are provided with internested spur gears 38, Fig. 4. The strips 34, 34' are laterally adjustable strips to regulate the spaces between the strips so that different sizes of creams may be handled. A knob 40 is fastened to one of the gears 38, and by turning said knob an attendant is enabled to adjust the bars 36 endwise and thereby move the strips 34 laterally in one direction, and the strips 34' laterally in the opposite direction, for the purpose stated, so that the channels between the twin metal strips will register with the size of the blanks.

Resting on the upper edge of the twin metal strips are equally spaced transverse bars 41 with outwardly projecting pins 42. The ends of said bars are connected to links of chains 43 which are run over disks 44 having outwardly widening notches 45 to receive alternately the transverse bars 41. The disks 44 are fastened on shafts mounted in standards 46. Said standards also support shafts 48 on which are idlers 47. The projecting pins 42 on the transverse bars 43 are fastened so that they register with the channels made between the twin metal strips 34 and when the chains 43 are driven by gears 49 said pins 42 will push the blanks through the channels and across the open work apron.

50 designates a container slotted on its underside. Paddles or plates 52 fastened on a shaft serve to agitate liquid coating supplied by pipe 53 to the container 50. A plate 54 having a slot like that of the container 50 is brazed or otherwise fixed on the underside of the container and a plate 54' similar to plate 54, being fastened a little lower. The slots in the two plates register with the slot of the container 50. In the opening between the two plates is positioned a plate 55 perforated at equal distances with letters or designs. The slots made by the perforated letters or designs are substantially at right angles to the slots in the container 50 thus leaving small openings and when the machine is operated, the liquid coating will run in one or more streams or strings upon a single blank, causing ridges corresponding to the letters or designs of plate 55. The plate 55 is clamped to rib 56 with a set screw so that it may be readily changed. 57 designates an eccentric strap and pulley. The end of the strap and the 65 rib 56 are loosely secured to a transverse bar

58 which slides in the slot of bracket 59 when the eccentric is rotated.

61 is a discharging apron mounted on transverse rollers 60, carried by a table 62, provided with supports 63.

64 designates tight and loose pulleys through which the machine is driven (see Figs. 1 and 2). 65 is a driving connection for the receiving mechanism. 66, 67 and 68, Fig. 3, are gears of a train; the gear 67 being arranged to actuate the vibrator and the gear 68 to drive the pushing mechanism. 69 is a driving connection for the discharge apron 61, and 70 a driving connection for the shaft 51 of the container 50.

The operation of the machine is as follows:—Water is let in at inlet 11 in tank 9 and being heated by steam or gas, not shown in the drawings, to the proper temperature the liquid coating is poured in container 13. The blanks placed on the receiving apron will, when the machine is operated, bring them in transverse rows in the channels on the open work table between the spray pipes 22 and 23 where they are coated, the excess of coating being thrown off and caused to fall back into the container 13. Before the blanks leave the open work table, the plate 55 is drawn across the slot of the slotted container 50 and hence the liquid coating runs in one or more strings or streams on to the blanks leaving ridges similar to the perforation in plate 55 on each of the blanks. As the blanks leave the open work table they are taken on the discharging apron 61 which runs into a cold room, not shown in the drawings, or they may be cooled off by some other device.

Having thus described my invention, what I claim as new and desire to secure by Letters Patent, is:—

1. In a coating machine a pair of transverse grooved rollers, a table having longitudinal spaced strips, endless ribbons between said strips and around said rollers, top and bottom transverse ribs fixed to said endless ribbons the bottom ribs registering with the grooves of said rollers, transverse rotary supports above the ends of said endless ribbons, transverse bars with outwardly projecting pins and registering with said rotary supports, and endless carriers connected to said transverse bars, the whole registering with the travel of said ribbons.

2. In a coating machine, an open work table comprising a pair of transverse bars, equally spaced vertical plates pointed at their ends and fastened in vertical slots of said bars, and band or coiled springs between said bars and fastened to the points of one end of said vertical plates, a vibrator with transverse roller arranged directly beneath said band springs and means to vibrate said roller and springs, pairs of longitudinal twin metal strips having their edges

slightly above said open work table and their ends upwardly bent, said ends being secured to an equally spaced slotted bridge support at one end and alternately 5 secured to a pair of movable slotted bars at the other end, means for opening and closing said twin metal strips, transverse bars with outwardly projecting pins and resting on said twin metal strips, their ends secured 10 to flexible bands, a rotary support for said flexible bands and means to impart travel to the rotary support.

3. In a coating machine, a lettering and 15 decorating device comprising a slotted container, an agitator in said container, and a movable plate perforated with letters or designs the length of their slotted openings at right angles to the slot of said container to 20 eject one or more flows of coating at a single blank, an open work table, evenly spaced channels above said table, means for adjusting the widths of said channels, a transverse rotary support above said channels, transverse bars with outwardly projecting 25 pins registering said channels, flexible conveyers, the ends of said bars being secured to the flexible conveyers and means for moving said conveyers.

4. In a chocolate lettering and decorating 30 device, a slotted container for said material, a plate perforated with letters or designs, means for moving said plate across the slot of said container, and means to agitate and

expel one or more flows of said material at a single blank.

5. The combination with a machine for applying coating material to blanks in which is comprised a holder for coating material and means for moving blanks to be coated in transverse rows beneath said holder, of a 40 lettering and decorating device having movable means for controlling one or more flows of the coating material at a single blank after their entire bodies have been coated.

6. The combination in a chocolate decorating apparatus, of a container having a slot in its underside, a movable plate perforated with letters or designs, and means for moving said plate across the slot of the 50 container.

7. The combination in a coating machine, of an open-work table comprising transverse bars having vertical slots, spaced vertical plates pointed at their ends and fastened 55 in said slots, springs disposed between the plates, means for moving blanks on the table, and agitating means disposed below the springs.

In testimony whereof I hereto affix my 60 signature in presence of two witnesses.

WILLIAM FRITZ.
